UNITED STATES PATENT OFFICE.

ABRAHAM GOLDER, OF EVERETT, MASSACHUSETTS.

COMBINATION LOCK.

Application filed April 20, 1928 Serial No. 271,505.

This invention relates to combination locks and has for its general object to provide a novel lock of this nature which is adaptable for a great variety of purposes, such for instance as locking a lid or cover to a box, locking a window, locking a drawer, etc.

The lock is designed to lock together two elements and it comprises a rotatable locking member carried by each of said elements, said members being arranged to rotate about axes at right angles to each other, and a finger carried by each element which co-operates with the locking member carried by the other element, the locking members and fingers being so arranged that they can be separated or unlocked only when each locking member is adjusted into a predetermined position.

In order to give an understanding of the invention I have illustrated in the drawings a selected embodiment thereof which will now be described after which the novel features will be pointed out in the appended claims.

Fig. 1 is a perspective view of a box embodying my invention;

Fig. 2 is a fragmentary front view showing the cover removed;

Fig. 3 is a rear side view of the cover;

Fig. 4 is a section on the line 4—4, Fig. 1;

Fig. 5 is a section on the line 5—5, Fig. 4.

The drawings show the invention as it might be applied for locking a cover, or closure to a box or other receptacle, but I desire to state that the invention is capable of a great variety of uses wherever it is desired to lock two elements together.

Referring to the drawings, 1 indicates a box or receptacle having an opening 2, and 3 is a cover, door or closure for the opening. This cover may be hinged to the box and thus be permanently connected thereto or may be entirely removable from the box as desired.

In the construction shown, which, however, is merely for illustrative purposes, the lower end of the cover is formed with a lip 4 to engage under a flange 5 situated at one end of the opening 2 thus holding the lower end of the cover in place. The box is also shown as having ribs 6 along its sides on which the side edges of the cover 3 rest.

My improved lock is shown as used for locking the upper end of the cover 3 to the box. It comprises two rotatable locking

members, one of which is shown at 7 and is carried by the box and the other of which is shown at 8 and is carried by the cover, together with two fingers 9 and 10 which co-operate with said locking members, one of the fingers, the finger 9, being carried by the cover and co-operating with the locking member 7 and the other finger, the finger 10, being carried by the box and co-operating with the locking member 8.

The locking member 7 is cup-shaped and is provided with the depending flange 11 provided with a slot 12. This locking member is mounted on a stud 13 which extends through the top of the box and is provided on its exposed end with a thumb piece 14 by which it may be turned. This thumb piece has suitable numbers, letters or other identifying marks on it to assist in properly setting it, as will be presently described. When the cover is locked in place the finger 9 on the cover is located behind the flange 11, as seen in Fig. 4.

The locking member 8 on the cover is in the form of a disk which is mounted on a stud 15 that extends through the cover, said stud being journaled at its inner end in a plate 16 that is spaced from the cover but attached thereto. The finger 9 on the cover is shown as being formed on this plate 16 although it might have any other suitable construction. The locking member 8 is located between the plate 16 and the cover 3.

The stud 15 extends through the cover and is formed on its outer exposed end with a thumb piece 17 by which the locking member 8 may be turned. This disk is provided on its periphery with numbers, letters or other identifying marks to assist in properly adjusting the disk. The locking member 8 is formed with a slot 18 and said member co-operates with the depending finger 10 formed on the box. When the cover is locked this finger is located between the locking disk 8 and the cover.

Thus normally when the lock is in operation the finger 9 on the cover is situated behind the flange 11 of the locking member 7 and the finger 10 on the box is situated between the locking member 8 and the cover. The cover is thus doubly locked in place by the two locking members which, it will be noted, are mounted to rotate about axes at right angles to each other.

In order to unlock the box the thumb piece 14 is turned into a position to bring the slot

12 in alignment with the finger 9 on the cover and the thumb piece 17 is also turned so as to bring the locking member 8 into a position in which the slot 18 therein is in 5 alignment with the finger 10. When this has been done then the upper end of the cover may be swung outwardly away from the box thus exposing the contents thereof as seen in dotted lines, Fig. 4.

10 In order to open the box it is necessary for one to know the proper combination, that is, to know the position in which to turn each of the thumb pieces 14 and 17 in order to align the slots 12 and 18 with the fingers 9 and 10.

15 It will be noted that one feature of the invention resides in having the two locking members, one carried by each of the two elements to be locked together and each rotatable about an axis at right angles to that of the other, together with the two fingers, one carried by each of the said two elements to be locked together and which co-operate with the locking members to lock the closure in place.

20 25 When the cover is to be locked it is only necessary to have the locking members properly adjusted so that when the cover is closed the fingers 9 and 10 will pass through the slots 12 and 18 after which the thumb pieces 20 may be actuated to upset the combination.

25 The fingers 10 and 9 are shown as located in line with each other but the upper end of the finger 9 is slightly below the lower end of the finger 10 so that when the cover is opened or closed the finger 9 can swing underneath the finger 10 without interfering.

30 My improved lock is relatively simple but is effective in operation.

I claim:

40 1. In a combination lock, the combination with two elements to be locked together, of a rotary locking member carried by each element, said locking members being rotatable about axes at right angles to each other, and 45 a finger on each element co-operating with the rotatable locking member on the other element to lock said members together.

2. In a combination lock, the combination with two elements to be locked together, a

locking member rotatably carried by each element, said locking members being rotatable about axes at right angles to each other, a finger on each element which is located behind the locking member on the other element, each locking member having a slot which may be brought into register with the corresponding finger by rotating said locking member.

3. The combination with a box having an opening, of a closure thereof, a locking member rotatably carried by the box and having an annular flange extending parallel to the axis of rotation, a second locking member rotatably mounted on the inside of the closure to turn about an axis at right angles to that of the flanged locking member, a finger on the cover situated behind the flange of the first-named locking member, a second finger on the box located behind the second-mentioned locking member and the cover, each locking member having a slot through which the finger may pass when the cover is being opened or closed, and means on the outside of the cover and box for rotating the locking members.

4. The combination with a box having an opening, of a closure thereof, a plate secured to the inside of the closure but spaced therefrom, a stud journaled in said plate and closure and extending through the latter, a locking member mounted on the stud, a finger carried by the box and adapted to be received between the locking member and the closure, a second locking member carried by the box and rotatable about an axis at right angles to that of the first-named locking member, said second locking member having a flange extending parallel to its axis of rotation, and said plate having a finger adapted to be received behind the flange, said flange and said first-named locking member each having slots through which the fingers may pass when the closure is closed or opened, and thumb pieces exterior of the box and closure by which the locking members may be turned.

5. In testimony whereof, I have signed my name to this specification.

ABRAHAM GOLDER.
